UNITED STATES PATENT OFFICE.

RUDOLF R. RADINSE, OF CLEVELAND, OHIO.

ROTARY BRUSH.

1,326,372.

Specification of Letters Patent. Patented Dec. 30, 1919.

Application filed June 23, 1919. Serial No. 306,205.

To all whom it may concern:

Be it known that I, RUDOLF R. RADINSE, a citizen of the United States, residing at Cleveland, in the county of Cuyahoga and 5 State of Ohio, have invented certain new and useful Improvements in Rotary Brushes, of which the following is a specification.

This invention relates to rotary brushes and more particularly to that type of brush 10 in which the bristles or wires are adapted to be fitted on or to be fastened to a rotary shaft.

An important object of the invention is in an improved means for preventing the 15 bristles from lateral movement, thereby preventing crystallization in the case of wire bristles causing them to break or fall off, this result being effected by the use of two metal rings which are clamped about the 20 bristles in a manner to be hereinafter described.

A further object of the invention is in the provision of means for holding the wires or bristles in place as particularly pointed 25 out in my former Patent No. 988,506, bearing date of April 4, 1911.

The invention has the advantage of requiring only a single central plate to hold the parts of the brush in place and accordingly the parts may be cheaply constructed 30 and easily assembled.

Referring to the drawings forming part of this specification and in which like reference numerals designate similar parts 35 throughout the various views, Figure 1 is a side elevation of a brush constructed in accordance with the principles herein set forth and Fig. 2 is a section on the line 2—2 of Fig. 1.

40 The device comprises a central plate 10 having an axial hole 11 by means of which it is fitted to a spindle or shaft and suitably clamped by any appropriate means.

At its outer edge this plate, which is sub- 45 stantially circular in plan, is provided with a series of tongues 12 which are integral therewith, these being stamped from a single piece of sheet metal of which the plate is formed; the tongues are alternately bent in 50 opposite directions so as to clamp a retaining ring 13 of twisted wire into the bands or twists, to which ring the wires, fibers or bristles 14 are woven or inserted, and then folded over so that the ends of the wires or 55 bristles extend outwardly or radially so as to

present the free ends to the work which may be applied to the brush.

Two flat rings 15 and 16 having an outside diameter greater and an inside diameter slightly less than the outside diameter of the 60 tongues are placed between the bristles and the tongues, and the provision of this plate prevents the bristles from bending over under pressure providing thereby a more uniform clamping arrangement between the 65 opposite tongues of the plate.

In assembling the parts the tongues are alternately sprung apart in opposite directions or toward the opposite side of the plate and the wire ring 13 with the bristles 70 attached thereto is inserted between said tongues. The rings 15 and 16 are then placed upon each side of the bristles, the tongues 12 are pressed together or clamped upon the plates, the pressure exerted there- 75 upon being sufficient to create a curving of the rings 15 at points between the tongues 12 and also enough to securely clamp the abrading wires or bristles in position. It has been found unnecessary to provide any 80 means to further securing the parts together, although it is obvious that the tongues may be riveted or welded to the rings 15 and 16 but this has the disadvantage of preventing the removal of any parts for re- 85 placement, consequently I prefer to leave the parts in a dis-united position further than is effected by the clamping due to the pressure exerted thereto. To insert new brush material it is merely necessary to pry the 90 tongues of one side apart permitting the removal of the wire 13 and the strands there- within and to substitute new parts for those removed.

It is obvious that various kinds of material 95 may be used for forming a brush, such as strips of cloth and the like when it is desired to use the brush for buffing purposes, this being clamped in the same manner as before described and while I have shown this par- 100 ticular form of device it is apparent that numerous other forms may suggest themselves to those familiar with the work required and I do not wish to limit myself further than is required by the state of the 105 art and to that which is within the scope of the appended claims.

Having thus described my invention, what I claim is:

1. A rotary brush comprising a plate hav- 110

ing tongues at the outer edge thereof, a pair of side rings extending around the edge of the plate between the tongues, and brush material clamped between the rings, and held by the pressure of the tongues on said rings.

2. A rotary brush comprising a plate having tongues at the outer edge thereof, a retaining ring fitting between said tongues, fibers connected to said ring and projecting

outwardly therefrom, and a pair of side rings clamped between the tongues at opposite sides of said retaining ring.

In testimony whereof, I do affix my signature in presence of two witnesses.

RUDOLF R. RADINSE.
